ILLUMINABLE SIGN

Jack Morgan, Chicago, Ill., assignor to Price Brothers, Inc., Chicago, Ill., a corporation of Illinois

Application August 23, 1950, Serial No. 11,891

Term of patent 3½ years

(Cl. D1—12)

To all whom it may concern:

Be it known that I, Jack Morgan, a citizen of the United States of America and resident of Chicago, in the county of Cook and State of Illinois, have invented a new, original, and ornamental Design for an Illuminable Sign, of which the following is a specification, reference being had to the accompanying drawing, forming a part thereof.

Fig. 1 is a front elevational view of an illuminable sign embodying my new design.

Fig. 2 is a view of one of the like ends thereof.

Fig. 3 is a back view thereof.

Fig. 4 is a plan view thereof.

The dominant features of my design are shown in full lines.

I claim:

The ornamental design for an illuminable sign, substantially as shown and described.

JACK MORGAN.
